AUTOMATIC OSCILLATOR FREQUENCY
CONTROL SYSTEM

Charles Travis, Philadelphia, Pa., assignor to Radio Corporation of America, a corporation of Delaware

Application February 4, 1935, Serial No. 4,793

8 Claims. (Cl. 250—20)

My present invention relates to superheterodyne receivers, and more particularly to improved methods of, and means for, automatically stabilizing the frequency of the local oscillator of a receiver of the superheterodyne type.

The modern superheterodyne receiver is often used under conditions such that the local oscillator frequency, at any setting of the manually operated tuner, tends to shift. Local oscillator frequency shift may be due to thermal changes as well as line voltage fluctuations. It is inherent in the superheterodyne principle that the accuracy with which tuning must be performed and maintained is directly proportional to the signal frequency. Present day short wave superheterodyne receiver design, for example, is not entirely adequate in regard to this accuracy. To keep the intermediate frequency (I. F.) within the middle ten percent of a 10 k. c. (kilocycles) pass band is not particularly difficult at broadcast frequencies (550 to 1500 k. c.). However, at 20 megacycles (m. c.) it requires an oscillator stability of one part in 40,000. This is equivalent to fair crystal control without temperature compensation. At 20 megacycles local oscillator variations due to thermal effects and line voltage fluctuations amount to many kilocycles; in fact, frequency drifts of 40 or 50 k. c. are too often encountered.

Automatic frequency control (AFC) has been proposed in the past to regulate the local oscillator frequency. The utility of such a system in connection with a short wave receiver is readily appreciated when it is pointed out that even a moderately successful AFC system in such a case would greatly reduce the potential frequency drift. A ratio of 25 to 1 would keep the signal carrier well within the I. F. pass band for a potential drift of as much as 50 k. c. It will be recognized that the desired station would not be entirely lost even though quality would suffer due to lack of alignment with the carrier.

For superheterodyne receivers used in the broadcast band the AFC system has many uses. Fine manual tuning required in high fidelity receivers to obtain best results could be avoided with such a system. The AFC, in general, may be said to be highly desirable for use in a superheterodyne receiver employed in a manner such that accurate tuning is important. In connection with remote tuning control systems an AFC system will be found valuable in providing the final adjustment that the remote control system is unable to effect.

Now, I have found, after investigation and ex- 55

perimentation, that an AFC system for a superheterodyne receiver should comprise a device, having frequency discrimination, which is capable of producing a control bias dependent upon the frequency of the intermediate frequency carrier, and an electronic local oscillator frequency control network, operated by the control bias, for adjusting the local oscillator frequency in a sense such that it differs from a desired signal frequency by the established intermediate frequency. From a generic viewpoint each of the circuits hereinafter disclosed includes this discriminating control bias generator, and a frequency control unit provided with an electronic device regulated by the control bias.

It may, therefore, be stated that it is one of the main objects of the present invention to provide an automatic frequency control for a local oscillator, wherein the control includes a discriminator network comprising a pair of differentially connected rectifiers which are mistuned by equal amounts above and below the mid-channel frequency of the intermediate frequency band; the discriminator functioning to provide a direct current bias voltage which is dependent upon the mid-channel frequency, and the bias voltage being utilized to vary an electrical characteristic of an electron discharge device in a manner such that the local oscillator frequency is adjusted to a desired value.

Another important object of my invention is to provide a system for automatically varying the frequency of an oscillator in a desired manner in response to the variations of a bias voltage generated by a network utilizing energy derived from the oscillator, the frequency varying system comprising a device for adjusting the reactance of the oscillator tank circuit without changing the load upon the latter.

Another object of the invention may be said to be the provision of a novel method of frequency control of the local oscillator of a superheterodyne receiver, the method including the steps of impressing the intermediate frequency energy upon a discriminator network capable of furnishing a direct current voltage whose magnitude is dependent upon the carrier frequency of said energy, and the direct current voltage being utilized to vary an electrode bias of an electron discharge tube employed to vary the resonant frequency of the local oscillator tank circuit.

Still another object of the invention is to improve automatic frequency control systems for superheterodyne receivers, the improvement comprising the reduction of the intermediate fre-

quency to a lower frequency, the derivation from the lower intermediate frequency energy of a control bias dependent in magnitude upon the lower frequency, and the employment of the control bias to regulate the magnitude of an electronic reactance in a sense to adjust the local oscillator frequency to a desired value.

And still other objects of the invention are to improve generally the efficiency of tuning of superheterodyne receivers, whether of the broadcast or short wave type, and more especially to provide automatic local oscillator frequency control systems for such receivers which are not only durable and reliable in operation, but readily manufactured and assembled in radio receivers.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawings:

Fig. 1 shows one embodiment of the invention,

Fig. 2 illustrates a modification,

Fig. 3 is a graphic analysis of the response characteristics of the discriminator in Fig. 2,

Fig. 4 graphically portrays the operation of the AFC system,

Figs. 5 and 6 show two modifications of the discriminator network used in Fig. 1,

Figs. 7, 8, 9 and 10 show four modifications of the local oscillator frequency control device used in Fig. 1,

Fig. 11 shows a modified form of an AFC system,

Fig. 12 schematically represents an AFC system applied to a superheterodyne receiver utilizing triple detection.

Referring now to the accompanying drawings, wherein like reference characters in the different figures designate similar circuit elements, there is shown in Fig. 1 a circuit diagram of a superheterodyne receiver employing an AFC system. The receiver is of a conventional type well known to those skilled in the art, and comprises a signal collector A, such as a grounded antenna circuit, coupled to a radio frequency amplifier having a variable tuning condenser device 1 in its input network. The amplifier may consist of more than one stage, and in such case the input of each stage would include a variable tuning condenser. The amplifier output is coupled to the tunable signal input circuit of the converter network, the input circuit including the variable tuning condenser 2.

The converter network comprises a tube 3 known in the art as a pentagrid converter tube, also designated as a 2A7 type tube (or 6A7 when used for automobile receivers); the tube is designed to perform simultaneously the functions of a first detector and local oscillator. Since the particular construction of tube 3, and its circuits, is not a part of this invention, only a brief description will be given of the circuits thereof. The tunable signal circuit of tube 3 is connected between the signal grid and the grounded cathode. The local oscillator section of the network comprises the local oscillator tank circuit 4 connected between the grounded cath-

ode and the first grid functioning as the local oscillator grid.

The second grid of tube 3 is magnetically coupled to the coil 5 of the tank circuit 4, and the 5 second grid therefore functions as the oscillator anode. The third and fifth grids act as screen grids for the fourth, or signal, grid. The resonant circuit 6 disposed in the plate circuit of tube 3 is tuned to the operating intermediate 10 frequency. The tank circuit 4 includes in addition to the variable tuning condenser 7, the padding condensers 8, 9 which function to keep the tuning of the tank circuit 4 "tracked" with that of the signal circuits.

15 The rotors of condensers 1, 2, 7 are arranged for mechanical uni-control, and the dotted lines 10 represent such control. A "manual tuner" knob 11 is used to adjust the rotors from the operating panel of the receiver. It is sufficient 20 for the purposes of this application to explain that the condenser 7 tunes the tank circuit 4 through an oscillator frequency range differing at all times from the common signal frequency range of the amplifier and converter input circuits by the frequency of the circuit 6. For illustrative purposes the operating I. F. is assumed to be 450 k. c. It is to be clearly understood, however, that in place of the composite converter network there may be employed independent first detector and local oscillator tubes 25 in a manner well known in the art.

Further, the signal frequency range may be the broadcast range, or it may be a short wave band.

The intermediate frequency energy in circuit 30 6 is transmitted to the diode second detector circuit of multiple duty tube 12 through a network including an I. F. amplifier. The latter may include one, or more, amplification stages, and is provided with an input transformer M₁ 35 having its primary and secondary circuits each resonated to the intermediate frequency; the output transformer M₂ is similarly designed. Both transformers are designed to pass substantially uniformly a band of frequencies including the carrier and its modulation side band frequencies. The tuned secondary circuit 13 of transformer M₂ is the input circuit of the diode second detector network.

The tube 12 is of the duplex diode-triode type, 40 50 also well known in the art as a tube of the 55 or 2A6 type; although it is to be understood that a pentode section may be used in place of the triode section of tube 12 (2B7 and 85 types). The diode anodes of tube 12 are strapped together, and 55 connected to the cathode side of grounded bias resistor 14 through a path including circuit 13 and load resistor 15, the latter being shunted by a radio frequency by-pass condenser 16. The triode section of tube 12 has its control grid coupled to a desired point on load resistor 15 for 60 deriving therefrom the audio component of the rectified intermediate frequency current. The amplified audio component in the plate circuit of tube 12 is then utilized in any desired manner.

65 The direct current component of the voltage developed across resistor 15 is used for AVC purposes. This may be accomplished in any manner well known in the art. By way of illustration the lead 17, designated as "AVC," is shown connected from the diode anode side of resistor 15 to the signal grid circuits of the radio frequency amplifier, the converter, and the intermediate frequency amplifier. The usual pulsating current filter elements 18, comprising a resistor and condenser, are disposed in the AVC connection.

Those skilled in the art are fully aware of the mode of operation of the AVC system. As the received signal amplitude increases, the signal grids of the controlled tubes are biased increasingly negative thereby reducing the gain of these controlled tubes. In this way the signal input to the second detector is maintained substantially constant over a wide range of signal amplitude variation at the antenna A.

It is to be understood that the controlled tubes can be progressively decreased in AVC bias. This is the method of AVC biasing employed at the present time; a tube receiving less signal energy thus has applied to it stronger AVC bias. Again, the AVC bias may be derived from a separate diode rectifier; or from a point preceding the detector input circuit 13 whereby there will be less selectivity to the AVC rectifier than to the detector. These arrangements are all well known in the art. The specific type of AVC circuit employed in the receiver is immaterial; the essential thing is that such a system coact with the AFC system hereinafter described to produce satisfactory local oscillator frequency control.

To secure automatic control of the frequency tank circuit 4 there is employed a network comprising a "Frequency changer" adapted to reduce the 450 k. c. I. F. to an I. F. of 50 k. c. The lower I. F. is then impressed upon a "Frequency discriminator" which functions to produce a control bias dependent in magnitude upon the lower I. F. The control bias is used to regulate the effect of an electronic device upon the tuning of the tank circuit 4.

Considering, now, the AFC system from a specific viewpoint, the converter 19 is of the same type as that shown in connection with tube 3. The I. F. energy is impressed upon the signal grid through coupling condenser 20, and the local oscillation network (not shown) is tuned to a frequency of 500 k. c. Thus, there is produced in the plate circuit of tube 19 a reduced I. F. of 50 k. c. Those skilled in the art will be capable of constructing the circuit details of network 19 from the disclosed circuits associated with tube 3. The plate circuit of network 19 is coupled to the frequency discriminator network, the latter including an electron discharge tube of the duo-diode type.

The tube 21 may be of the type shown in connection with the tube 12; in that case the grid and plate will be left free and only the diode anodes 22 and 22' are used. The plate circuit of tube 19 includes a pair of coils 23, 24 arranged in series. Coil 23 is coupled to resonant circuit 23'; the latter is tuned to one side of the I. F. of 50 k. c. by a predetermined frequency amount. Thus, circuit 23' is tuned to 49 k. c. Coil 24 is coupled to resonant circuit 24', the latter being tuned to the other side of the I. F., as for example to 51 k. c. The diode anode 22 is connected to the cathode of tube 21 through a series path including circuit 23' and resistor 25, the latter being shunted by a by-pass condenser, and the low alternating current side of circuit 23' being grounded.

The diode anode 22' is connected to the cathode of tube 21 through a series path including circuit 24' and resistor 26, the latter being shunted by a by-pass condenser. The anode side of resistor 26 has connected to it a lead 27, designated as "AFC"; the lead comprising the path through which the control bias developed in the discriminator is applied to the electronic frequency control device. The lead 27 includes a resistor-con-

denser network 28 which functions to suppress pulsating components in the control voltage transmitted through lead 27. A grounded switch 29 is connected to lead 27, and its function will be explained in detail at a later point.

The device which functions to change the tuning of the tank circuit 4 comprises an electronic reactance element. It includes an electron discharge tube 30, which may be, for example, of the screen grid type. A bleeder resistor 31, grounded at one end and connected at the other end to the +B side of the receiver voltage supply source, furnishes the requisite operating potentials of the electrodes of tube 30. The lead 27 is connected to the control grid of tube 30 through a resistor 32, and a condenser 33 of a predetermined magnitude is connected between the control grid and anode of the tube. The control grid of the latter is also connected to the oscillator grid side of tank circuit 4 through a blocking condenser 34.

The operation of the AFC system shown in Fig. 1, as well as the characteristics of the component units thereof, will now be explained. In general, the operation of the AFC system is dependent on a change in I. F. An undesired change of local oscillator frequency changes the response of the discriminator. This, in turn, causes a variation in the control bias fed to the grid of tube 30. There results, as a consequence, a change in the reactance of the tank circuit 4 in a direction such as to restore the tank circuit frequency to the desired value. The essential elements of the system are the discriminator and the reactance control device.

Considering the characteristics of the discriminator, it can be stated that the latter should be constructed so that it will not be affected by adjacent channel signals. For this reason the frequency discriminator must be preceded by a certain amount of I. F. selectivity, and the input for the discriminator is therefore taken off somewhere at, or near, the end of the I. F. amplifier. The system shown in Fig. 1 utilizes a second frequency changer network to reduce the 450 k. c. I. F. to 50 k. c. This second I. F. of 50 k. c. is employed to get greater selectivity in the frequency discrimination device. The frequency discriminator itself is shown as comprising a pair of differentially connected diode rectifiers, the rectifiers being mistuned by equal amounts above and below the mid-channel frequency.

By utilizing the differentially connected rectifiers in the frequency discriminator network the output of the network depends solely on frequency of the carrier. A change in carrier amplitude in that case only affects the sensitivity of the control action. In spite of this a satisfactory AVC system is desirable. As stated before the diode rectifiers of the discriminator are connected differentially. That is to say, the difference of the rectifier outputs is utilized as the control bias to be transmitted through lead 27. Instead of employing diode rectifiers, it is possible to utilize in the balanced detector arrangement a pair of plate circuit detectors arranged in push-pull. However, it is more desirable to employ diode rectifiers, because such an arrangement gives the difference in output directly.

The point on resistor 26 to which lead 27 is connected is at a negative direct current potential with respect to ground when the input from circuit 24' is greater than that from circuit 23', and it will be positive with respect to ground in the reverse case. When the I. F. is exactly between the resonant frequencies of circuits 23'

and 24', the inputs to the two rectifiers balance, and the point on resistor 26 to which lead 27 is connected will, therefore, be at ground potential. Accordingly it will be seen that the magnitude and polarity, with respect to ground, of the voltage of point Z on resistor 26 is wholly dependent upon the frequency value of the intermediate frequency energy produced in the plate circuit of tube 19.

The device which changes the frequency of the tank circuit 4 is shown in the system of Fig. 1 as being of the type comprising an electron discharge tube whose control grid to cathode capacity is utilized as a tuning condenser across tank circuit 4. Without entering into any extended and detailed discussion of the electrical characteristics of tube 30 and its associated circuits, it is pointed out that the effect of the condenser 33 connected between the control grid and anode of tube 30 is to augment the capacitative magnitude of the control grid to cathode capacity of tube 30. It has been shown that in such a network, variation of the bias of the control grid results in a variation in the magnitude of the control grid to cathode capacity.

Reference is made to application Serial No. 638,514 of Jacob Yolles, filed October 19, 1932, patented Oct. 15, 1935 as U. S. P. 2,017,270, for a disclosure of a voltage operated electronic condenser device which may be utilized, with suitable change of circuit constants for the purposes of the present invention. The magnitude of condenser 33 is chosen so as to furnish a control grid to cathode capacity suitable for adjustment of the frequency of tank circuit 4. It will be seen that this control grid to cathode capacity is connected in series with condenser 34, and both capacities are connected in shunt across the variable tuning condenser 7. Hence, by varying the bias of the control grid of tube 30 with respect to ground, there is secured a variation in the magnitude of the capacitative reactance which has been described as in shunt with tuning condenser 7. As the bias of the control grid of tube 30 is made negative, the gain of tube 30 is reduced, and the control grid to cathode capacity magnitude is diminished. This results because the magnitude of this capacity is dependent upon the gain of tube 30.

It will now be seen that a change in the frequency of the intermediate frequency energy, flowing in the plate circuit of tube 19, away from the lower I. F. frequency of 50 k. c. results in a simultaneous shift of the frequency of tank circuit 4. Of course, it will be understood that the change in the control grid to cathode capacity magnitude of tube 30 is to be in that direction which will cause the tank circuit frequency to be restored to its desired value. Those skilled in the art will be able to choose suitable constants for the circuits of the AFC system disclosed in Fig. 1 to suit the particular signal and oscillator frequency ranges employed.

Merely by way of example, let it be assumed that the signal frequency to which the set is tuned is 1500 k. c. In that case the frequency of the tank circuit 4 which is required in the production of the 450 k. c. I. F. is 1950 k. c. If, for some reason or other, the frequency of tank circuit 4 changes to 1951 k. c., there will be produced in the output circuit of the I. F. amplifier energy of 451 k. c. Since the second frequency changer is operating with a local oscillator frequency of 500 k. c., it follows that the second intermediate frequency energy, produced in the

plate circuit of tube 19, will have a frequency of 49 k. c. Since this frequency of 49 k. c. is that of the circuit 23', the point Z will have a direct current potential which is positive with respect to ground, due to rectification in the rectifier circuit including diode anode 22.

As a consequence the bias of the control grid of tube 30 will be positive thereby increasing the gain of tube 30, and increasing the magnitude of the control grid to cathode capacity of tube 30. An increase in this control grid to cathode capacity magnitude results in an increase in the total capacity in the tank circuit 4; it therefore follows that the frequency of the tank circuit will be reduced. It will be understood that the constants of the oscillator frequency control device are so chosen that a change in frequency of the tank circuit away from the desired frequency value will result in the production of control bias at point Z in the discriminator network sufficient in magnitude to vary the control grid to cathode capacity of tube 30 in that sense which will restore the tank circuit frequency to the desired value. In the illustrative case given above, the control grid to cathode capacity of tube 30 will be increased to such a point that the frequency of the tank circuit 4 will be decreased from 1951 k. c. to 1950 k. c. Those skilled in the art will readily be able to work out the circuit constants for the reverse case wherein the tank circuit frequency shifts to a value below the desired value.

A practical difficulty of the receiving system shown in Fig. 1 is found in the difficulty of dislodging a strong signal to make way for a weaker one on a closely adjacent channel, without having the weaker station jump right across the band to disappear on the other side. To overcome this difficulty the switch 29 is used; the function of the switch is to ground the bias voltage derived from point Z, and render the AFC system inoperative during tuning. After the signal has been tuned in the switch 29 may be opened, and the ground connection removed. The manner of closing switch 29 during tuning depends upon the construction of the controls of the receiver. If there are too many operating controls on the panel of the receiver, it will be advisable to mechanically couple switch 29 with the tuning knob 11 so that the switch 29 will be automatically closed when the operator's hand moves the tuning knob. This is schematically illustrated in Fig. 1 by the dotted line 10. Reference is made to U. S. P. 2,038,332, issued to E. Zadig, for an illustration of such a mechanism.

For example, the tuning knob may be depressible against a spring to close switch 29, and rotary motion of the tuning knob then instituted to vary the position of the rotors of the tuning condensers. Any other mechanical arrangement can be employed to keep the switch 29 closed during tuning of the receiver. If there are not many controls on the receiver panel, the switch 29 may be operated as a separate switch to be used only before tuning from one station to another one.

In Fig. 2 there is shown a modification of the superheterodyne receiver system shown in Fig. 1, only the AFC circuit details being shown in detail. It is to be understood that except for the AFC system, the receiver is substantially the same as that shown in Fig. 1. To preserve simplicity of description, appropriate designations are used by way of reference to the omitted circuit networks of the receiver. The receiving system

shown in Fig. 2 was found satisfactory in operation, and was employed for receiving short wave signals of a frequency of the order of 7500 k. c. The I. F. employed was 450 k. c., but the second frequency changer employed a local oscillation of 400 k. c. to produce the second I. F. of 50 k. c.

The frequency discriminator network in this modification composed a pair of resonant circuits 40 and 41 arranged in series in the plate circuit of the second frequency changer tube 19. The circuit 40 was tuned in this case to 51 k. c., while the circuit 41 was tuned to 49 k. c. The diode anode 22 of tube 21 was connected to the cathode thereof through a path which included in series coil 40' and the load resistor 25'. The diode anode 22' was connected to the cathode of tube 21 through a path which included the coil 41' and the load resistor 26' arranged in series. Coil 40' was coupled to circuit 40, while coil 41' was coupled to circuit 41. A negative potential was applied to the low alternating potential side of coil 40', while the lead 27 was again connected to point Z. Thus, it will be seen that the frequency discriminator network of the AFC system of Fig. 2 differs from that shown in Fig. 1, in that the plate circuit of the frequency changer tube 19 includes the mistuned circuits feeding the differentially connected diode rectifiers.

The oscillator frequency control device is substantially different from that shown in Fig. 1. In this type of control device there is employed an electron discharge tube 42 of the triode type, and the control bias produced at point Z is utilized to vary the cathode resistance of tube 42. Variation of the cathode resistance of tube 42 results in a variation of the reactance of the tank circuit 4. This was accomplished by magnetically coupling a coil 43, disposed in the grounded cathode lead of tube 42, to the feedback coil 44 of the first frequency changer tube 3. This arrangement is equivalent to more or less short-circuited turns loosely coupled to the inductance coil in the tank circuit 4. As the grid of tube 42, which may be of the 76 type, is made less negative the turns become more closely short-circuited, and vice versa. It was found that the AFC system shown in Fig. 2 gave satisfactory control of the frequency of tank circuit 4 for the signal frequency range employed. It should be noted that source 42' provided the no-signal bias for tube 42. Since the latter has no self-bias, as in Fig. 1, the anode 22 returns to a point negative to ground.

Considering the operation of the system shown in Fig. 2, it is pointed out that the frequency change of the tank circuit 4 occurs because the effective inductance of the tank circuit is varied by the bias change on control tube 42. The leakage inductance of the coil 43 (turns not 100 percent coupled to 4) is in series with the variable cathode resistance of 42. This is equivalent to throwing more inductive reactance across the coil when the negative bias is reduced, which raises the frequency, and vice versa. If the series reactance is a condenser, we have capacitive reactance across the tank coil, and reducing the negative bias lowers the frequency.

With the proper choice of the circuit constants of the system shown in Fig. 2 it was possible to eliminate microphonic troubles due to frequency modulation of the local oscillator at short waves. Such frequency modulation appears when the signal is slightly off resonance. The time constant of the filter in the AFC line must be small for this purpose.

The direct current output of the balanced rectifier circuit of the system in Fig. 2, which comprises the discriminator, is depicted in Fig. 3. This figure shows the response characteristic of each of the rectifiers (dotted lines). It, also, shows the differential, or net output, response of the network (full line curve). The solid line curve of Fig. 3 is a representation of the variation of AFC bias with frequency of the signal energy impressed on the discriminator.

The operation of the AFC system is graphically represented in Fig. 4. The ordinates represent oscillator tank circuit capacity, and abscissae represent frequency. The latter may be taken either as the oscillator frequency or that of the I. F. signal carrier, as the two vary together and differ by a constant amount equal to the radio frequency signal frequency. As the carrier is caused to traverse the I. F. transmission band, AFC bias generated by the differential rectifier network varies according to an S-shaped curve similar in form to dash line curve a_1 to d_1 . This bias, acting upon the oscillator frequency control tube and associated circuit, varies the reactance reflected across the oscillator tank; which may be translated into terms of capacity, and the curve a_1 to d_1 may be thought of as representing equivalent capacity thrown across the tank circuit by the control means. Let it be assumed that the operation of the system in Fig. 1 is being considered.

The total effective capacity is related to oscillator frequency by the nearly straight line a_2 — d_2 . A portion of this total is physically present, not due to variations in the control tube, and variable, for example, only by manual means. This physical capacity is the difference between the total capacity and that thrown into the tank circuit by the control tube, and is represented by the solid curve, a_2 — b_2 — c_2 — d_2 . This curve may be regarded as the control characteristic of the system.

If the tank capacity is continuously decreased, as by manual tuning, the oscillator frequency, and with it the I. F. carrier frequency, increases progressively until the point a_2 is reached. Thereafter instability occurs; for an increase in frequency brings about a decrease in total capacity by means of the AFC action which further increases the frequency, and so on. What happens is that the I. F. carrier frequency jumps abruptly to a_3 . Thereafter operation is stable until c_2 is reached, at which point a second jump occurs to c_3 . Traversing the band in the opposite direction the jumps occur at d_2 to d_3 , and at b_2 to b_3 . Throughout the segment b_2c_2 stable operation occurs, and it is here that the desired control obtains. The ratio of the slope of b_2c_2 to that of the straight line a_2d_2 is the sensitivity of the control; this slope represents the ratio of a potential variation in the (uncontrolled) oscillator frequency to that which actually occurs when the control is operative.

Under optimum conditions the local oscillator frequency might be changed by as much as 200 k. c. for a 10 percent change in G_m of the control tube. Using the type 76 tube as a control, this 10 percent change requires a change of grid bias of almost exactly 0.4 volt. I have found, using only fair coils peaked 10 k. c. apart at an I. F. of 450 k. c., that 10 volts variation in AFC bias from peak to peak is readily obtainable without overloading. On this basis, a control sensitivity of 500 to 1 is conservatively possible.

If control of this sensitivity be maintained at

all signal frequencies, the oscillator drift in short wave receivers will reduce to perhaps a hundred cycles, and even at three meters a superheterodyne would hold in tune as closely as the present broadcast receiver. Naturally, the problem is rather that of obtaining a fraction of this sensitivity without undue complications.

If the discriminator rectifier connections are reversed, the double kink in the control characteristic is inverted, and the two sides of the band become regions of stability, with instability over the center. Control obtains on the two edges of the band, and the I. F. carrier can be made to jump from one edge to the other, but will not remain in the center. This, also, occurs with the properly poled connections, if the signal is tuned in at the image position.

The present invention is not limited to the driving of the discriminator network as shown in Figs. 1 and 2. In Figs. 5 and 6 are shown two different modifications of this portion of the AFC system. Fig. 5 shows the tuned diode rectifiers of Fig. 1 supplied with signal energy from the I. F. amplifier through separate driver tubes 50, 51. Thus, the I. F. energy is supplied to amplifier 50 for amplification and subsequent impression on the tuned circuit 23'; amplifier 51 functioning to amplify I. F. energy prior to impression on tuned circuit 24'. The discriminator network of Fig. 5 differs from that shown in Fig. 1 in that the I. F. is not reduced to a lower value.

In Fig. 6 there is shown an arrangement wherein in the plate circuit of the last I. F. amplifier includes in series the primaries feeding tuned circuits 13, 23' and 24'. The I. F. amplifier may use, in this case, a 58 type tube having a high R_p . This mode of connection can be used as common coupling effects do not interfere with the desired discrimination between higher and lower frequencies. Here, also, the I. F. is not reduced in value as in Figs. 1 and 2.

The local oscillator reactance changer unit may be varied in construction. Figs. 1 and 2 show two different forms of reactance changers. Figs. 7 to 10 inclusive illustrate further modified arrangements which may be employed for the desired function. In each figure it is to be understood that the tank circuit is that shown in either Fig. 1 or Fig. 2, and that the AFC bias may be derived from the discriminator networks shown in the latter systems, or those shown in Figs. 5 and 6.

In Fig. 7, the frequency control tube has its plate impedance vary with the bias upon the grid. When coupled to the tank circuit through condenser 60 (whose reactance is equal to R_p), the frequency change of the tank circuit, in kilocycles, for a given proportionate variation in R_p is independent of frequency, and is fixed by the time constant of R_p and the tank tuning capacity. If the latter is made as small as possible, for example of the order of 20 mmf., and the R_p of the tube is 10,000 ohms, a ten percent change in the latter will produce a frequency shift of 20 k. c.

The frequency control tube in Fig. 8 has its R_m

$$\left(\text{mutual or trans-resistance } \frac{1}{G_m} \right)$$

ternating potential side of the tank circuit through condenser 60. A choke 61 connects the cathode to ground. If the tube R_m is thus utilized instead of the R_p , its center value may be of the order of 1000 ohms, and the same percentage change in resistance will give a frequency shift of 200 k. c. The mean frequency should be large compared with the shift.

The arrangement in Fig. 10 is equivalent to that in Fig. 8. The cathode of the control tube is grounded, and the plate and grid, connected by the large blocking condenser 62, are connected to the high alternating potential side of the oscillator tank circuit through condenser 60. The R_m of the control tube is here utilized instead of the R_p .

The frequency control variant in Fig. 9 is intended to be a fixed reactance in series with a variable resistance of approximately equal magnitude, (as in Fig. 7); but in Fig. 9 the variable resistance is $1/(G_m + G_p)$ instead of being R_p as in Fig. 7. Condenser 33 is large to place all the plate voltage on the grid; condenser 34 is small and is the fixed control reactance. The electrodes of the tube 30 are energized in substantially the same manner as shown in Fig. 1. The high potential side of the oscillator tank circuit is here connected to the plate side of condenser 34 through condenser 33. Without entering into a detailed analysis of the characteristics it is pointed out that the output impedance is a function of the current amplification of the tube, and that the relation is an inverse one.

In Fig. 11 is shown another AFC system modification; both the discriminator network and frequency control unit being modified and different from those disclosed up to this point. A portion of the I. F. carrier voltage at the input of the second detector is impressed upon the grid of tube T_1 . The receiver up to the second detector may be the same as that shown in Fig. 1. In the plate circuit of this tube the primaries P_1 and P_2 , of two similar I. F. transformers M_4 and M_5 are connected in parallel, and tuned to the exact center of the I. F. band; the resonance curve of this composite primary is broadened by the shunt resistance R_1 of from 25,000 to 50,000 ohms. The secondaries S_1 and S_2 are tuned respectively at equal increments above and below the I. F. band mid-frequency.

Owing to the presence of R_1 across the common primary the latter is essentially a constant voltage source, and, as there is no direct coupling between the two secondaries, the total effective coupling between the latter is negligible. The secondaries each operate into one of the anodes of double diode rectifier T_2 having a common cathode which is ungrounded for direct current. This connection gives a direct current output which is the difference between the rectified voltages from the two diodes. At a frequency near the resonance of S_1 the output is negative, while at a symmetrical frequency near the resonance of S_2 it is positive.

It is necessary to separate the resonant points of the two secondaries S_1 and S_2 by a minimum amount approximately equal to the I. F. mid-band frequency divided by the Q

$$\left(\text{or } \frac{wL}{r} \text{ ratio} \right)$$

of the circuits. At 450 k. c., without considering losses introduced by the primary and by the diode load, a value of Q of 200 is about the highest that can be obtained in the usual size com-

and R_p utilized in shunt combination to give a lower minimum value of variable tube resistance. The plate and grid are by-passed to ground, while the cathode is connected to the high al-

mercial I. F. coils. This corresponds to a minimum separation of 2.25 k. c. between the two secondary resonant points. After losses are accounted for, a separation of 4 or 5 k. c. would probably be excellent at this frequency. If a more selective discriminating device were necessary, recourse must be had to bulkier coils, or else a double heterodyne system used as in Fig. 1, the tube T_1 operating as a converter with its output circuit tuned to a new and lower second I. F., 50 k. c. for example. The output from the balanced rectifier network is impressed upon the grid of the control tube T_3 . This tube, by means of any of several possible forms of reactive coupling circuit, causes the frequency of the oscillator to vary in accordance with the AFC bias, tending to return the I. F. carrier to the center of the I. F. band.

In the arrangement of Fig. 11 the coupling reactance is an inductance; this takes the form of a coil loosely coupled to the oscillator tank inductance. The excess inductive admittance of this coil is tuned out by a variable condenser across the control tube. The coupling becomes the familiar case of loosely coupled resonant circuits. This is the form of control circuit shown in Fig. 11. It is well known that if the tuned winding 80 is loosely coupled, as at M_6 , to the tank circuit 81 of the local oscillator the frequency of the latter may be considerably changed by varying the tuning of the coil 80 , and, other things being equal, the amount of variation depends upon the damping of the circuit including coil 80 . For the present purpose the coil 80 is mistuned by a fixed amount, and the damping is varied by the variable shunt tube resistance. This method was experimented with in the 4 to 10 megacycle band, and it was found that a frequency variation of about one percent could be obtained over the whole band. It is pointed out that in this particular case one of the chief reasons for AFC would be to compensate for physical changes in the tank circuit due to thermal expansion, warpage and the like. The variable condensers in circuits 80 , 81 are uni-controlled in order to keep the impedance reflected across the tank circuit a combination of a reactance and resistance of equal magnitude, or essentially so. This is the 45° condition, and results in no change in load on the tank circuit when the resistance is changed (electronically), and likewise maximum change in frequency. If the reactance and resistance were very unequal, there would be a small change in frequency and a relatively large change in load. The uni-control is not intended to tune the circuits to the same resonant point; the control circuit is tuned so that it was always reactive, by an amount equal in this case to the average R_p of the tube.

In Fig. 12 there is shown an AFC system applied to a receiver wherein is used the repeated application of the heterodyne principle, with the controlled oscillator operating at a fixed frequency, lower than that of the first tunable oscillator. Without the frequency control feature, this is equivalent to a short wave converter connected to the input of a receiver intended for a lower frequency band; in the present case the second unit is provided with fixed input tuning. In the circuit a signal frequency of 50 megacycles has been taken as a concrete example, and a nominal first I. F. of 2 megacycles has been assumed. It is further assumed that unwanted variations in the first oscillator may cause the

actual I. F. to vary by ± 100 k. c. The coupling means between the output of the first converter and the input to the second is a band pass filter capable of passing 200 k. c. The second I. F. must be at least one half of this band width if image interference is to be avoided. The second I. F. of 175 k. c. is demodulated. It is also used for frequency control.

Thus, the discriminator and frequency control operate on the second local oscillator. Frequency drifts as high as 100 k. c. in either direction from 2175 k. c. will be corrected by the AFC system. Specifically, there may be employed in the AFC system of Fig. 12, the discriminator network of Fig. 11 followed by the frequency control unit of Fig. 7. It is not believed necessary to include a specific disclosure of the last named particular AFC system to be employed in Fig. 12, as those skilled in the art will readily appreciate the manner of accomplishing this from the foregoing detailed description.

This particular superheterodyne method is employed for the 50 megacycle signal range to provide a fixed nominal frequency for the oscillator to be controlled, it being simpler to control a non-tunable oscillator than one that is tunable over a wide coverage band. A frequency in the neighborhood of 2 megacycles is shown for this second controllable oscillator as this seems to be optimum to obtain a wide AFC variation in k. c. A very low frequency is not good because a large percent change would be required, and a very high frequency is subject to a limitation from tube capacities.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

I claim:

1. A superheterodyne receiver comprising a frequency changer network including a local oscillator circuit, means for tuning the oscillator circuit over a wide frequency range, an intermediate frequency network, means for demodulating the intermediate frequency energy, a resonant discriminator network adapted to have intermediate frequency energy impressed thereon, said discriminator being constructed and arranged to produce a direct current voltage whose magnitude and polarity are solely dependent upon the frequency of said impressed energy, a variable reactance element connected in said local oscillator circuit as a supplemental tuning device and including an electron discharge tube, and means for impressing the direct current voltage produced by said discriminator upon a gain control electrode of said last named tube whereby the frequency of said local oscillator circuit may be increased or reduced to a predetermined frequency of said wide range selected by said tuning means, and a device, actuated by tuning adjustment of said tuning means, for automatically rendering said voltage impressing means ineffective.

2. A superheterodyne receiver comprising a frequency changer network including a local oscillator circuit, means for tuning the oscillator circuit over a wide frequency range, an intermediate frequency network, means for demodulating the intermediate frequency energy, a second frequency changer network for decreasing

the frequency of the output of said intermediate network to a substantially lower intermediate frequency thereby to increase the rejection of adjacent channel signals, a discriminator network adapted to have said lower intermediate frequency energy impressed thereon and producing a direct current voltage whose magnitude is solely dependent upon the frequency of said impressed energy, a variable reactance element connected in said local oscillator circuit as a supplemental tuning device and including an electron discharge tube, and means for impressing the direct current voltage produced by said discriminator upon a gain control electrode of said last named tube whereby the frequency of said local oscillator circuit may be adjusted in a predetermined direction at any setting of said tuning means, and said discriminator network comprising a pair of rectifiers differentially connected, one rectifier being tuned to a frequency above said lower intermediate frequency, and the other rectifier being tuned to a frequency below the lower intermediate frequency.

3. A superheterodyne receiver comprising a frequency changer network including a local oscillator circuit, means for tuning the oscillator circuit over a wide frequency range, an intermediate frequency network, means for demodulating the intermediate frequency energy, a resonant discriminator network adapted to have intermediate frequency energy impressed thereon and producing a direct current voltage whose magnitude and polarity are solely dependent upon the frequency of said impressed energy, a variable reactance element connected in said local oscillator circuit as a supplemental tuning device and including an electron discharge tube, and means for impressing the direct current voltage produced by said discriminator upon a gain control electrode of said last named tube whereby the frequency of said local oscillator circuit may be adjusted in a predetermined direction at any setting of said tuning means, and a second frequency changer network for reducing the frequency value of said intermediate frequency energy prior to impression upon said discriminator network to an extent sufficient greatly to increase the selectivity of the latter thereby preventing the discriminator from being affected by adjacent channel signals.

4. In a superheterodyne receiver of the type including a signal input circuit, a local oscillator circuit, said oscillator circuit having main and auxiliary frequency determining elements, said auxiliary frequency determining element comprising an electron discharge tube, a frequency changer, and an intermediate frequency network tuned to a carrier frequency F_1 , a resonant circuit tuned to a frequency slightly below F_1 , means to rectify alternating voltage developed in the resonant circuit, a second resonant circuit tuned to a frequency slightly above F_1 , means to rectify alternating voltage developed in the second resonant circuit, means to supply energy from the intermediate frequency network to said resonant circuits, and means responsive to the difference between said rectified voltages to vary the gain of said frequency determining tube in such a sense as to cause the frequency of energy transmitted through the intermediate frequency network to approach more nearly to F_1 , a switch device for rendering the last means ineffective, and said main frequency determining element being constructed to actuate said switch device upon adjustment of the former.

5. In a superheterodyne receiver of the type including a signal input circuit, a local oscillator circuit, said oscillator circuit having main and auxiliary frequency determining elements, said auxiliary frequency determining element consisting solely of an electron discharge tube having an inductive impedance in its cathode circuit reactively coupled with the inductance of said oscillator circuit, a frequency changer having electrodes connected to said signal and oscillator circuits, and an intermediate frequency network tuned to a carrier frequency F_1 coupled to the frequency changer, a resonant circuit tuned to a frequency slightly below F_1 , means to rectify alternating voltage developed in the resonant circuit, a second resonant circuit tuned to a frequency slightly above F_1 , means to rectify alternating voltage developed in the second resonant circuit, means to supply energy from the intermediate frequency network to said resonant circuits, the selectivity of the intermediate frequency network between the frequency changer and said resonant circuits being sufficiently high to prevent response of said rectifying means to adjacent channel signals, and means responsive to the difference between said rectified voltages to vary the gain of said frequency determining tube in such a sense as to cause the frequency of energy transmitted through the intermediate frequency network to approach more nearly to F_1 .

6. In a superheterodyne receiver of the type including a tunable signal circuit, and a tunable local oscillator network, means for simultaneously varying the tuning of said signal and local oscillator networks, an additional means in the local oscillator network for maintaining a constant frequency difference between the signal and local oscillator networks as the tuning means is varied, an intermediate frequency amplifier network, an auxiliary network comprising a pair of tuned circuits, each of said pair of tuned circuits being electrically associated with said intermediate frequency amplifier network, one of said pair of tuned circuits being tuned to a frequency differing from the intermediate frequency by a value less than five kilocycles, and the other of said pair of circuits being tuned to a frequency greater than said intermediate frequency by a similar value, a rectifier connected across each of said pair of tuned circuits, an auxiliary frequency control device for said local oscillator network, said device comprising an electron discharge tube having at least one electrode thereof reactively coupled to said oscillator network, and means responsive to a differential direct current flow of said rectifier circuits for adjusting the gain of said auxiliary control tube in a sense such that the energy impressed upon said pair of tuned circuits is made to approach in frequency said intermediate frequency value, a switch device for rendering the gain adjusting means ineffective, and said tuning means being arranged to actuate said switch device upon adjustment of the tuning means.

7. A method of receiving signals of a desired frequency which includes combining collected signals with locally produced oscillations of a different frequency to produce signals of a difference frequency, amplifying the last signals, demodulating the amplified signals of said difference frequency, reducing the amplified signals to a substantially lower frequency to increase the selectivity with respect to desired sig-

nals, deriving a direct current voltage from the lower frequency signals in response to departure of the latter from the said lower frequency value, and adjusting the frequency of said locally produced oscillations with said direct current voltage in a sense to maintain said lower frequency value.

8. In a superheterodyne receiving system of the type employing a signal input network and a local oscillator arranged to produce local oscillations whose frequency differ from a desired signal frequency by a predetermined heterodyne frequency, means for amplifying the heterodyne

energy, means for detecting the amplified heterodyne energy, means to increase the selectivity of the system relative to desired signals, said last means comprising a frequency reducing network for reducing the heterodyne energy to a substantially lower frequency, and means, responsive to a departure of the reduced heterodyne energy from said lower frequency value, for automatically adjusting the frequency of said oscillator in a sense to maintain said reduced heterodyne energy at the lower frequency value.

CHARLES TRAVIS.
